UNITED STATES PATENT OFFICE.

WALTER SCOTT, OF HOT SPRINGS, SOUTH DAKOTA.

RAILWAY TIME-SIGNAL.

SPECIFICATION forming part of Letters Patent No. 482,699, dated September 13, 1892.

Application filed May 13, 1892. Serial No. 432,872. (No model.)

To all whom it may concern:

Be it known that I, WALTER SCOTT, of Hot Springs, in the county of Fall River and State of South Dakota, have invented a new and 5 Improved Railway Time-Signal, of which the following is a full, clear, and exact description.

The object of the invention is to provide a new and improved railway time-signal which 10 is simple and durable in construction, very effective and automatic in operation, and arranged to positively and accurately record the time when a train passes the track on which the device is applied.

15 The invention consists of a time-clock provided with a stopping mechanism for an auxiliary clock adapted to be released by an electro-magnet releasing mechanism of especial construction.

20 The invention also consists of certain parts and details and combinations of the same, as will be fully described hereinafter, and then pointed out in the claims.

Reference is to be had to the accompanying 25 drawings, forming a part of this specification, in which similar letters of reference indicate corresponding parts in all the figures.

Figure 1 is a front elevation of the improvement as applied and with parts broken out. 30 Fig. 2 is an enlarged sectional rear elevation of the improvement on the line 2 2 of Fig. 3. Fig. 3 is a transverse section of the same. Fig. 4 is a face view of the connection between the two blocks, and Fig. 5 is a side elevation of 35 a spring-plate arranged alongside the track for making the electric contact.

The improved railway time-signal is provided with a suitably-constructed casing A, supported on a post A', arranged alongside 40 the track, as is plainly indicated in Fig. 1. The ends of the casing A are provided with the dials B and B', on which indicate the hour and minute hands C C', respectively, actuated by an auxiliary spring-actuated clock 45 mechanism D, arranged within the casing A. Within the casing A is also located a second clock mechanism E, actuating two sets of minute and hour hands F and F', somewhat smaller in size than the sets of minute and hour hands 50 C C' and indicating on the smaller dials B² and B³, formed within the dials B and B', re-

spectively, as will be readily understood by reference to Figs. 1 and 3.

On the minute-shaft E' of the clock mechanism E is secured a pinion E², in mesh with 55 a gear-wheel G, mounted to rotate loosely on a shaft D', forming part of the auxiliary clock mechanism D and carrying a gear-wheel D², in mesh with a pinion D³, secured on the minute-shaft D⁴ of the said auxiliary clock mechanism D.

On the inner face of the loose gear-wheel G is formed a spring-arm G², on which is adapted to abut one end of an arm H, secured on a shaft H', mounted to turn in suitable 60 bearings on one face of the gear-wheel D², previously mentioned, the said shaft extending radially from the hub of the wheel D², in which one end of the shaft has its bearing, the outer end of the shaft having its bearing in a 65 box H², attached to the rim of the said wheel D². (See Fig. 4.)

Near the inner end of the shaft H' is secured an arm H³, extending approximately at 70 right angles to the arm H and pivotally connected with a rod H⁴, fitted to slide transversely in the hub of the gear-wheel D². The outer end of the rod H⁴ is formed with a screw-thread, on which screws a nut H⁵, adapted to be locked in place by a jam-nut H⁶. 75

On the face of the nut H⁵ rests a lever I, extending vertically and formed at its upper end with a hook I', adapted to engage a tooth on a stop-wheel J, secured on the shaft D⁵ of the wind-wheel of the auxiliary clock mechanism D. 80

On the lever I, opposite the nut H⁵, presses a collar K, on which rests one end of a spring K', coiled on the rod H⁴ and resting at its other end on a fixed part of the frame of the auxiliary clock mechanism D. The spring K' presses on the collar K, so as to hold the lever I in contact with the nut H⁵. The lever I has its pivot I² mounted in bearings attached to the framework of the auxiliary clock mechanism D, and from the said pivot extends downward an arm I³, formed at its inner edge with a notch I⁴, the bottom of which is inclined, as at I⁵, and is adapted to engage the outer end of the armature-lever L of electro-magnets N, located within the casing A. The armature-lever L is pivoted at L' in the frame 95 100

of the auxiliary clock mechanism D, and is held off the cores of the electro-magnets by a spring L³. (Shown in Figs. 2 and 3.)

The electro-magnets N are connected by 5 the usual wires N¹ and N² with contact-points N³ and N⁴, respectively, of which the contact-point N⁴ is located on one of the ties of the railroad-track, while the other contact-point is formed on the under side of a spring-plate 10 O, arranged alongside one of the track-rails and adapted to be engaged by the flange of the passing car-wheel, so that when this takes place the spring-plate O is pressed downward and the contact-points N³ and N⁴ are 15 moved in contact with each other to establish an electric circuit in the magnets N.

The armature-lever L is loosely engaged at its under side and near the outer end by one end of a bell-crank lever P, pivoted on the 20 framework of the auxiliary clock mechanism D, the said bell-crank lever being pivotally connected by a link P' with a lever P², pivoted on the post A'. The lower end of the lever P² is connected by a link P³ with a bell-crank 25 lever P⁴, pivotally connected with a lug O', formed on the under side of the spring-plate O, at one side of the contact-point N³, as will be readily understood by reference to Fig. 5. Now when the car-wheel passes over the 30 spring-plate O and depresses the same to establish a circuit, as above described, then at the same time the bell-crank lever P⁴ is actuated by the said plate O moving downward. The movement of the bell-crank lever P⁴ 35 causes a pull on the link P³, which imparts a swinging motion to the lever P², and the latter by being connected with the bell-crank lever P causes a raising of the armature soon after the contact has been made, as before 40 described. Thus when the electric circuit is closed the armature-lever L is attracted, but only for an instant, as then the plate O causes the lever P to swing, as before described, to return the armature-lever to its former normal position, in which it is finally held by 45 the spring L³. Now as soon as the armature is attracted by the closing of the circuit the free end of the said lever travels up the incline I⁵ in the bottom of the notch I⁴ of the 50 arm I³ of the lever I, whereby the arm I³ is free to swing inward as soon as the armature-lever travels into the enlarged part of the notch I⁴. As soon as the arm I³ is thus unlocked an unlocking of the lever I takes place, 55 the latter being forced outward out of engagement by its hook I' with the wheel J, caused by the pressure of the spring K' on the washer K, resting on the inner side of the said lever I. As soon as the wheel J is released by the lever I the auxiliary clock mechanism D is unlocked and is now actuated by its spring in the usual manner, so that a rotary motion is imparted to the wheel 60 D² by the pinion D³ on the minute-shaft D⁴. The wheel D² rotates until the arm H, carried by the said wheel, comes in contact with 65 the spring-arm G' on the wheel G, and as

soon as the said arm strikes the spring-arm G' the said lever is turned slightly, thus causing a turning of the shaft H' and an inward movement of the arm H³, held on the said shaft H'. The inward movement of the arm H³ causes a pull inward on the rod H⁴, and as the latter is connected with the outer surface of the lever I by means of the nut H⁵ the said lever is again swung inward to engage with its hook I' the wheel J, and the latter is thus again locked and further rotation of the auxiliary clock mechanism is prevented. Now it will be seen that the continuously-going 80 clockwork E has advanced the wheel J to a position corresponding to the hour of the day indicated by the sets of hour and minute hands F F'. Now when the auxiliary clock-work mechanism is actuated, as before described, and the wheel D is actuated its hands C and C' indicate on the dials B and B', respectively, until the auxiliary clock mechanism D is stopped at the time the lever H strikes the arm G'. When this takes place, 90 the minute and hour hands C and C' of the auxiliary clock mechanism assume a position corresponding to that of the minute and hour hands F F', indicating the time of day. Thus it will be seen that when a train passes the 95 plate O and depresses the same, as before described, then the sets of minute and hour hands C are actuated until they come to a stop, indicating the exact time of the day as given by the hands F F' of the regular clock 100 mechanism E. It will further be seen that the hour and minute hands C C' remain in this position, as further movement of the auxiliary clock mechanism D ceases, as before described, as soon as the lever H strikes the 105 spring-arm G'. The regular clock mechanism E continues in its movement—that is, the wheel G is rotated so that the arm G' moves away from the lever H and when a second train passes and actuates the plate O then the 110 auxiliary mechanism is again released, as above described, and causes a rotation of the wheel D² until the lever H again strikes the arm G', and the above-described operation 115 is then repeated. The hour and minute hands C C' are then moved from their former position again to a position on the dials B B' corresponding to the position of the sets of hands F F' on the dials B² and B³.

Having thus fully described my invention, 120 I claim as new and desire to secure by Letters Patent—

1. In a railway time-signal, the combination, with a time-clock indicating the time of the day, of an auxiliary clock mechanism, an 125 electro-magnetic releasing mechanism for the said auxiliary clock mechanism, and a stop mechanism, substantially as described, controlled from said time-clock and arranged to stop the auxiliary clock mechanism, the said stop mechanism comprising a lever fulcrumed on a wheel of the auxiliary clock mechanism and adapted to abut on an arm on one of the said wheels of the time-clock, a rod connected 130

with the said lever, and a stop-lever connected with the said rod and adapted to engage a stop-wheel on the wind-wheel shaft of the said auxiliary clock mechanism, substantially as shown and described.

2. In a railway time-signal, a stopping mechanism comprising an arm held on a revoluble gear-wheel, a wheel mounted to turn and carrying a lever adapted to abut on the said arm, a rod connected with the said lever and fitted to slide in the hub of the said second wheel, and a stop-lever connected with the said rod, substantially as shown and described.

3. In a railway time-signal, a stopping mechanism comprising an arm held on a revoluble gear-wheel, a wheel mounted to turn and carrying a lever adapted to abut on the said arm, a rod connected with the said lever and fitted to slide in the hub of the said second wheel, a stop-lever connected with the said rod, and a spring pressing on the said stop-lever, substantially as shown and described.

4. In a railway time-signal, a stopping mechanism comprising an arm held on a revoluble gear-wheel, a wheel mounted to turn and car-

rying a lever adapted to abut on the said arm, a rod connected with the said lever and fitted to slide in the hub of the said second wheel, a stop-lever connected with the said rod, a spring pressing on the said stop-lever, and an armature-lever controlled by electro-magnets and having its free end extending into a notch in the said stop-lever, substantially as shown and described.

5. In a railway time-signal, the combination, with an electro-magnet, of a releasing device for the armature-lever of the said electro-magnet and comprising a plate adapted to be actuated by the wheels of the passing train, a lever engaging the said armature-lever, and intermediate mechanism for connecting the said second lever to impart a swinging motion to the latter when the said plate is pressed, substantially as shown and described.
